Specification for Design.

Patented Mar. 29, 1921.

Application filed January 20, 1921. Serial No. 438,747. Term of patent 14 years.

To all whom it may concern:

Be it known that I, ROBERT F. MILLER, a citizen of the United States, residing at Indianapolis, in the county of Marion and State of Indiana, have invented a new, original, and ornamental Design for Radiator-Caps, of which the following is a specification, reference being had to the accompanying drawings, forming a part thereof.

Figures 1 and 2 are top plan and side elevational views, respectively, of the radiator caps showing my new design.

I claim:

The ornamental design for a radiator cap, as shown.

In witness whereof, I have hereunto set my hand and seal at Indianapolis, Indiana, this 17th day of January, A. D. nineteen hundred and twenty-one.
